UNITED STATES PATENT OFFICE.

WILLIAM J. KEENE, OF CHICAGO, ILLINOIS, ASSIGNOR TO CHICAGO SPRING BUTT COMPANY, OF CHICAGO, ILLINOIS, A CORPORATION.

SPRING-HINGE.

1,081,752.

Specification of Letters Patent.

Patented Dec. 16, 1913.

Application filed August 16, 1912. Serial No. 715,350.

To all whom it may concern:

Be it known that I, WILLIAM J. KEENE, a citizen of the United States, and a resident of the city of Chicago, county of Cook, and 5 State of Illinois, have invented certain new and useful Improvements in Spring-Hinges, of which the following is a full, clear, and exact description.

The invention relates to double acting 10 spring hinges for doors and the like, and more particularly to hinges of the type set forth in the prior application, Serial No. 535,951, filed in the United States Patent Office January 3, 1910, by George W. Schuster 15 and myself.

The present invention seeks to provide an improved construction of hinge frame and improved fastening means by which the hinge is secured to the door.

20 The invention also seeks to provide an improved form of fastening plate which is adapted to be secured to the door and is arranged to directly engage the post which is fastened to the floor plate and whereon 25 the hinge frame is pivoted, to thereby form a more secure connection between the floor plate and the door, and a construction better adapted to withstand the side pressure brought upon the door in swinging it to 30 and fro.

A further object of the invention is to provide a simple and effective adjustment for alining the door in central position.

The invention consists in the features of 35 improvement hereinafter set forth, illustrated in the preferred form in the accompanying drawing, and more particularly pointed out in the appended claims.

In the drawings, Figure 1 is a longitudinal section of the improved hinge shown in 40 position upon the door. Figs. 2 and 3 are inverted plan sections on the lines 2—2 and 3—3, respectively, of Fig. 1. Fig. 4 is a view of the inner end of the hinge. Figs. 5 and 6 are detail views, with parts shown in 45 section on the lines 5—5 and 6—6, respectively, on Fig. 1, illustrating the adjusting device for alining the door.

The hinge frame comprises upper and 50 lower parallel bars 1 and 2 formed of strap iron or steel. The lower bar is U-shaped and is provided with upturned end portions 3 and 4, the latter end portion having an outwardly projecting, horizontal extension 5. The upper bar 1 of the frame overlies the

extension 5 and is secured thereto by a rivet 6 and beyond the extension the upper bar is preferably provided with a down-turned end portion 7 which is adapted to abut against the end of a rabbet or recess which is cut 60 in the corner of the door 8 to receive the hinge. The opposite end of the upper frame bar 1 is secured to the up-turned end portion 3 preferably by means of a lug 9 on the bar seated in a notch in the upper end of the portion 3. A pair of transverse plates 10 and 11 extend between the upper and lower bars and are secured in position by lugs 12 thereon extending through openings in the bars and headed over, as shown. The plate 11 is 70 arranged closely adjacent the up-turned end portion 4 of the lower bar 2, and the cross-piece 10 is arranged near the inner or pivot-end of the hinge frame.

A floor plate 13 is adapted to be fixed in 75 position beneath the lower corner of the door and this plate has rigidly secured thereto an upwardly projecting post 14 upon which the hinge frame is pivoted. The post is preferably journaled in the upper 80 and lower bars. In the form shown, a bushing 15 is fitted within an opening in the lower bar and forms a bearing for the post. Immediately above the bushing the post is provided with an enlarged portion 16. The 85 reduced upper end of the post extends through a bushing 17 which is set within an opening in the upper bar. A dished ring 18 fits over the reduced upper end of the post and rests upon a shoulder 19 thereon. 90 This ring and the bushing 17 are suitably shaped to receive a row of anti-friction balls 20 which sustain the greater part of the weight of the door.

A spring actuated bolt or plunger 21 is 95 slidably mounted within the hinge frame or casing. This bolt or plunger extends loosely through openings formed in the cross bars 10 and 11 and in the up-turned end portion 4 of the lower frame bar. At its inner end, the bolt is provided with a head or yoke 22 which extends between the enlarged portion 16 of the post and the ball-bearing member 18 and which is provided with a longitudinal slot 23 through which the portion of the post between the part 16 thereof and its upper reduced end extends. This portion of the post fits the longitudinal slot 23 and forms a guide for the inner end of the sliding bolt or plunger. 110

The outer end of the plunger or bolt 21 extends loosely through two transverse slots 24 and 25 formed in the cross piece 11 and in the end portion 4 of the lower frame bar, as most clearly shown in Figs. 5 and 6. A guide block 26 fits between the vertical pieces 4 and 11 and between the upper and lower bars 1 and 2, as shown. The outer end of the bolt is guided in an opening in this block and the latter is adjustable from side to side to aline the door in closed position.

The adjustment of the block 26 is effected by a transverse screw 27 threaded therethrough. Washers 28 fixed to the ends of the screw engage the edges of the parts 4 and 11 so that the screw is held against longitudinal movement. One end of the screw is provided with a slotted head so that the screw may be rotated in opposite directions to move the guide block and the outer end of the plunger laterally in one or the other direction.

At its inner end the head or yoke 22 on the bolt is provided with a depending lug 29 having a transverse face which is arranged to engage a pair of rollers 30. These rollers are arranged within recesses formed in the enlarged portion 16 of the post and are mounted on opposite sides of the axis of the post upon pins 31, the ends of the pins being suitably secured to the enlarged portion 16 of the post.

A heavy spring 32 coiled about the plunger extends between the cross piece 10 and an adjusting nut 33 mounted upon a screw-threaded portion of the plunger inside of the cross piece 11. When the door is shifted in one or the other direction, one of the rollers 30 co-operates with the lug or abutment 29 to shift the plunger inwardly and compress the spring 32. When the pressure on the door is relieved, the spring acts to return the door to normal central position and to hold it in such position. In its longitudinal shift the plunger is guided at its inner end upon the post 19 and at its outer end in the guide block 26.

The hinge frame is adapted to be seated in a recess or rabbet cut in the lower corner of the door 8. A fastening plate or strip 34 is provided with openings for receiving screws 35 whereby it is secured in position to the edge of the recess or rabbet, as shown. The fastening plate 34 preferably extends the full length of the hinge frame and, when the latter is in position, the upper bar 1 thereof rests against the plate 34 and its down-turned end portion 7 abuts against the end of the recess. The horizontal extension 5 of the lower bar, the outer end of the upper bar and the plate 34 are all provided with openings for receiving a fastening screw or screws 36 whereby the outer end of the hinge frame is secured in position. The

upper reduced end of the pivot bolt 14 projects above the upper bar 1 of the hinge frame and the fastening plate 34 is provided with an opening 37, the walls of which engage and bear upon the upper end of the post. By this arrangement a more direct connection is formed between the door and the floor plate, since the fastening plate 34, which is secured to the door, directly engages the pivot post rising from the floor plate, so that the frame of the hinge is relieved, to a considerable extent, of the side strain brought upon the door in swinging it to and fro. Preferably, the opening 37 is slightly elongated, as shown in Fig. 3, and the plate 34 is provided with a down-turned tongue 38 which is adapted to extend through an opening 39 in the frame bar 1 and interlock with the edge thereof upon the longitudinal movement of the frame relatively to the plate. The slot 37 permits this longitudinal movement, but the side walls thereof snugly engage the upper end of the post, so that they form an additional bearing for the post and also serve, as stated, to relieve the hinge frame from side strains brought upon the door.

The entire construction is such that in applying the hinge it is only necessary to cut a recess in the corner of the door having straight plane faces which can be readily formed with two saw cuts. It is not necessary thereafter to form additional recesses or rabbets in the edge of the door. Finishing plates 40, secured to the opposite faces of the door by screws 41, extend over and inclose the hinge frame. A finishing plate 42 fits upon the upturned inner end portion 3 of the lower frame bar 2. This plate is provided with inturned edges 43 which slidably engage the edges of the portion 3. The inturned edges at their lower ends rest upon the bar 2 and, when the hinge is in position, the door extends over the upper edge of the plate 42 and holds it in place.

One of the finishing plates 40 is preferably provided with an opening 44, so that access is afforded to the adjusting screw 27. By turning the latter in one or the other direction, the outer end of the hinge frame and the guide block 26 are relatively adjusted and the door to which the hinge frame is secured can thus be alined or adjusted properly in its central closed position.

It is obvious that changes may be made in the details set forth without departure from the essentials of the invention as defined in the claims.

I claim as my invention:

1. In a spring hinge, the combination of a post adapted to be secured to the door frame, a hinge frame adapted to be seated in the recessed corner of the door and pivotally mounted on said post and a plate interposed between said hinge frame and door and

- adapted to be secured thereto, said plate having a bearing arranged to engage the upper edge of said post, substantially as described.
5. In a spring hinge, the combination of a hinge frame adapted to be seated in a recessed corner of the door and comprising upper and lower parallel bars connected at their ends, a plate adapted to be interposed between the edge of the recess and said hinge frame and to be secured to the edge of the recess, said plate and said frame having interlocking parts, a floor plate and a pivot post fixed to said floor plate and extending through said frame bars, the upper end of said post being extended above the upper bar of said hinge frame and having a bearing in said plate, substantially as described.
10. In a spring hinge, the combination of a hinge frame adapted to be seated in the recessed corner of the door and comprising upper and lower parallel bars connected at their ends, a plate adapted to be secured to the edge of the recess and against which the upper bar of said hinge frame abuts, a floor plate, and a post fixed to said floor plate, journaled in said frame bars and projecting above said upper bar, said plate having an opening, the walls of which engage the upper projecting end of said post, substantially as described.
15. In a spring hinge, a frame adapted to be seated in the recessed corner of the door and comprising a lower bar having upturned end portions with a horizontal extension projecting from the upper end of one of said end portions, an upper bar secured to said up-turned ends and overlying said extension, said extension and the overlying end of said upper bar having openings to receive fastening screws and means for securing the opposite end of the frame to the door, substantially as described.
20. In a spring hinge, a frame adapted to be seated in the recessed corner of the door and comprising a lower bar having upturned end portions with a horizontal extension projecting from the upper end of one of said end portions, an upper bar secured to said up-turned ends and overlying said extension and having an end portion extending downwardly over the end of said extension and adapted to abut against the end of the recess, spring actuated parts mounted in said frame and a stationary post journaled in said frame bars and having means for operatively engaging said spring actuated parts, substantially as described.
25. In a spring hinge, a frame adapted to be seated in the recessed corner of the door and comprising upper and lower bars connected at their ends, and a fastening plate
- adapted to be secured to the edge of the recess and against which fastening plate the upper bar of said frame abuts, said frame and fastening plate having interlocking parts and having also registering openings for fastening screws, substantially as described.
30. In a spring hinge, a frame adapted to be seated in the recessed corner of the door and comprising upper and lower bars connected at their ends and a fastening plate adapted to be secured to the edge of the recess, said plate and said frame having interlocking parts adapted to be engaged by the relative longitudinal movement of said frame and a stationary post whereon said frame is pivoted, said plate having a slot, the walls of which bear upon the opposite sides of the upper end of said post, substantially as described.
35. In a spring hinge, a hinge frame adapted to be seated in the recessed corner of the door and comprising upper and lower parallel bars, said lower bar having an integral up-turned portion at one end provided with a horizontal extension secured to said upper bar, a plate adapted to be interposed between said upper frame bar and the edge of the recess and to be secured to the door and to said upper frame bar, a stationary post pivoted in said frame bars and having its upper end projecting beyond said upper frame bar, said plate having an opening for receiving the upper projecting end of said post, a longitudinally shiftable, spring actuated bolt having a bearing at its inner end on said post and extending at its outer end through the up-turned portion of said lower frame bar, and parts mounted on said post for operatively engaging said bolt, substantially as described.
40. In a spring hinge, a hinge frame adapted to be seated in the recessed corner of the door, a post whereon said frame is pivoted, a longitudinally sliding, spring actuated bolt mounted in said frame, and having a combined sliding and pivotal engagement with said post, said post having parts arranged to engage and shift said bolt longitudinally, a laterally shiftable guide block mounted in the outer end of said frame and having an opening through which the outer end of said bolt extends, and means for relatively adjusting said frame and guide block in lateral direction, substantially as described.
45. In a spring hinge, a hinge frame comprising upper and lower bars with connecting end pieces integral with one or the other of said bars, a cross piece extending between said bars adjacent the outer end portion, a pivot post journaled in the inner ends of said frame bars, a longitudinally shiftable, spring actuated bolt mounted in said frame, said post having means for operating
50. In a spring hinge, a hinge frame adapted to be seated in the recessed corner of the door and comprising upper and lower bars connected at their ends, and a fastening plate
55. In a spring hinge, a hinge frame adapted to be seated in the recessed corner of the door and comprising upper and lower bars connected at their ends, and a fastening plate
60. In a spring hinge, a hinge frame adapted to be seated in the recessed corner of the door and comprising upper and lower bars connected at their ends, and a fastening plate
65. In a spring hinge, a hinge frame adapted to be seated in the recessed corner of the door and comprising upper and lower bars connected at their ends, and a fastening plate

said bolt, and said bolt being guided at its inner end upon said post, a guide block for the outer end of said post mounted between said upper and lower frame bars and between said cross piece and the adjacent end piece of the frame, and an adjusting screw threaded through said guide block and held

against movement longitudinal relatively to said frame, substantially as described.

WILLIAM J. KEENE.
